UNITED STATES PATENT OFFICE

VICTOR E. PETERSON, OF BROOKLYN, NEW YORK, ASSIGNOR TO J. R. WOOD & SONS, INC.,
OF BROOKLYN, NEW YORK, A CORPORATION OF NEW YORK

DESIGN FOR A WEDDING RING

Application filed August 23, 1932. Serial No. 44,675. Term of patent 14 years.

To all whom it may concern:

Be it known that I, VICTOR E. PETERSON, a citizen of the United States, residing at Brooklyn, in the county of Kings and State of New York, have invented a new, original, and ornamental Design for a Wedding Ring, of which the following is a specification, reference being had to the accompanying drawing, forming part thereof, in which

Fig. 1 is a top plan view showing my new design; and

Fig. 2 is a perspective view.

I claim:

The ornamental design for a wedding ring, as shown.

VICTOR E. PETERSON,
